US00D461466S

(12) **United States Design Patent**
Oakley et al.

(10) Patent No.: **US D461,466 S**
(45) Date of Patent: **** Aug. 13, 2002**

(54) **ENCLOSURE FOR ELECTRONIC CIRCUITRY**

(75) Inventors: **Nicholas W. Oakley**, Portland, OR (US); **Mark S. Smith**, San Jose, CA (US)

(73) Assignee: **3Com Corporation**, Santa Clara, CA (US)

(**) Term: **14 Years**

(21) Appl. No.: **29/129,818**

(22) Filed: **Sep. 21, 2000**

(51) LOC (7) Cl. **14-03**

(52) U.S. Cl. **D14/242**

(58) Field of Search **D14/137, 240, D14/138, 242, 308, 356, 357, 358, 311, 313, 441, 144, 348-355, 370, 341-347, 125, 432, 433, 155, 299, 257, 439, 140, 188, 230, 241, 243, 245, 379/433.01-433.13, 419, 434, 428.01-428.04, 420.01-420.04, 440, 441, 442; 455/550-575, 90; D13/184, 123, 152, 147, 110**

CLAIM

The ornamental design for an enclosure for electronic circuitry, as shown and described.

DESCRIPTION

FIG. 1 is a front isometric view of the present invention; FIG. 2 is a front view of the present invention; FIG. 3 is a left side view of the present invention; FIG. 4 is a right view of the present invention; FIG. 5 is a rear view of the present invention; FIG. 6 is a bottom view of the present invention; and, FIG. 7 is a rear isometric view of the present invention.
